ATTY

UNITED STATES PATENT OFFICE.

THOMAS TARLETON, OF WEMBLEY PARK, ENGLAND.

PENCIL-LEAD SHARPENER.

1,158,582.

Specification of Letters Patent.

Patented Nov. 2, 1915.

Application filed May 28, 1914. Serial No. 841,449.

To all whom it may concern:

Be it known that I, THOMAS TARLETON, subject of the King of Great Britain, residing at "Heathcote," The Drive, Wembley Park, in the county of Middlesex, England, have invented new and useful Improvements in or Relating to Pencil-Lead Sharpeners, of which the following is a specification.

This invention relates to pencil lead sharpeners of the type having two plates, one or both of which are provided with a rasping surface, the plates being spaced apart, and inclined to one another and adapted to be held together by spring pressure.

The object of this invention is to provide an improved device for sharpening pencil leads.

In pencil sharpeners of this type as hitherto constructed, the plate or plates provided with a rasping surface have been exposed and when the plates have been connected together by a spring or hinge the connection has been at or beyond the edges where the plates are nearest to one another.

According to this invention the plate or plates provided with a rasping surface is or are disposed within a casing provided with a slot, which slot is adapted to be closed to hold the powdered lead and to act as a guard to prevent the nose of the lead holder (which forms the body of the pencil) from becoming injured when the lead is being sharpened, the slot not being wide enough to allow the nose of the lead holder to come into contact with the rasping surface and further the plates are pivoted at or near the edge where the plates are farthest apart and so arranged that when the pencil lead is inserted between the plates they are moved apart against the action of the spring.

Figure 1 is a diagrammatic section of one form of pencil lead sharpening device made in accordance with this invention to an enlarged scale. Fig. 2 is a plan of the cover. Fig. 3 is a plan of the casing. Fig. 4 is a development of the casing. Fig. 5 is a plan view of the rasp holder. Fig. 6 is a development of the rasp holder. Fig. 7 is a plan of the rasp. Fig. 8 is a plan of the spring.

The plate *a* is provided with a rasping surface and is pivoted by pins *b* in the slots *c* in the holder *d*. The holder is provided with a slot *e* adapted to engage with

a pin *f* in the base of the casing *f*. A T-slot *g* is provided in the holder *d* to engage 55 a pin *h* in the base of the cover *h*. The casing is provided with a fixed plate or guide *m* against which the pivoted plate *a* is pressed by a spring *n*. The cover *h* is provided with a longitudinal slot *p* adapted to 60 cover or uncover the slot *j* as the cover is rotated to the limit permitted by the pin in the T-slots. The slot *j* is disposed longitudinally between the fixed and pivoted plates.

In use when it is desired to sharpen a pencil lead the cover is rotated to uncover the longitudinal slot *j*, the lead is then inserted between the fixed and pivoted plate and sharpened by suitable motion against the rasping face or faces. The device may be 70 made in any form so that it can be closed to prevent the powdered lead escaping and causing inconvenience. The point obtained can be flat or conical with more or less acute angle as may be desired. 75

The slot *j* of the casing *f*, together with said casing, acts as a guard and protects the pencil lead holder from becoming injured when sharpening the lead. The acuteness of the point is or may be determined by the 80 extent to which the lead is inserted between the plates.

What I claim and desire to secure by Letters Patent is:—

A pencil sharpener comprising a cylindrical casing, a longitudinal slot in said casing, a plate formed in one with the casing and lying within the casing, a cylindrical cover adapted to surround the cover, a longitudinal slot in said cover, a cylindrical rasp 85 holder disposed within the casing, a rasp pivoted to the holder and lying within the casing, a spring between the rasp and the holder and adapted to press one edge of the rasp against the plate, means for turning 90 the cover in respect of the casing, so that the slot in the cover may register with the slot in the casing or otherwise. 95

In testimony whereof I have signed my name to this specification in the presence of 100 two subscribing witnesses.

THOMAS TARLETON.
